UNITED STATES PATENT OFFICE.

ERNST R. HAASE, OF NEW LONDON, CONNECTICUT.

GRAPHOPHONE NEEDLE.

Application filed March 5, 1925. Serial No. 13,387.

My invention has reference, in its broad aspect, to improvements in graphophone needles of the type designed especially for use with disc records; and more particularly it is my purpose to provide a graphophone needle with a point of iridium or other metal which is practically permanent and will function to greatly improve the quality of reproduction of the instrument to which it is applied; first, by effecting the elimination of so called "surface noises" such as scratching and the like; second, by softening and clarifying the reproduced tones and especially those of a high frequency or register such as lyric soprano female voices; third, by bringing out the quality of soft toned instruments such as harps, flutes, violins, and the like, and rendering the reproduction of selections executed upon such instruments more accurate and pleasing; and, fourth, by effecting a more clear and accurate reproduction of vocal selections, particularly with reference to enunciation.

To the end that the above and other equally important objects and advantages may be attained, I have formed my needle with a hollow, medial or central cavity which is relatively insensitive to sound impulses productive of surface noises and strays, and within this cavity I interpose loosely a pin or plunger, the insertion or removal of which respectively affects the loudness or softness of the reproduction. The shank of my needle is formed with a bend intermediate its length from which the point extends at an angle opposed to the bend and laterally toward the graphophone reproducer. By so directing the point a much more effective contact with a record is obtained.

The structural elements employed to accomplish the above and other results and objects, and the method followed in forming the graphophone needle and arranging the elements of the same, will be hereinafter more fully described in detail and pointed out in the claims, but the scope of my invention may only be determined by the limits of the appended claims.

In the accompanying drawings wherein is illustrated one embodiment of my invention;—

Figure 1 is a detail view of my needle applied to a graphophone reproducer of conventional type,

Figure 2 is a longitudinal sectional view

of the needle, and a portion of the needle bit, and

Figure 3; view A shows a front elevation of my needle, and view B a view similar to A but with the needle turned to illustrate the relative angular relationship of the parts thereof.

In the drawings wherein like characters of reference designate like or similar parts throughout the several views;—

The numeral (1) designates a conventional reproducer assembly, in the bit (2) of which is removably retained by the usual set screw (3) my needle (4) for engagement with the record (5).

My needle (4) is formed with a bend (6) intermediate its length so that the lower portion (7) of the needle is given a direction more nearly vertical to the record (5) than the upper portion (8) thereof which is retained in the bit (2) of the reproducer. In practice the body of my needle is preferably formed by drawing out a hollow metallic wire or the like, so that the central needle cavity (9) is gradually restricted toward the lower end of the portion (7) of the needle. A record engaging iridium point (10) of a shape generally approximating the cross-sectional configuration of a record groove is affixed to the lower end of the portion (7) in any suitable manner and extends at an angle reverse to the bend as shown clearly in Figure 2, and angularly with respect to the reproducer as shown in view B of Figure 3. The purpose of so affixing and directing the point (10) is to provide a more effective contact with the walls of the record groove.

Loosely mounted within the central cavity (9) of the needle and extending substantially the length of the portion (8) thereof is a pin or plunger (11) formed with a head (12). The insertion or removal of the plunger functions respectively to produce a louder or softer quality of reproduction than would otherwise be obtained; it being known in the art that the tone volume is in direct proportion to the size and resistivity of the needle.

It is believed that the operation and advantages of my invention are apparent from the foregoing, but it is desired to again emphasize the peculiar formation of the central cavity, the plunger or pin, and the relative angular arrangement of the respective parts of the needle and the point of iridium

or other metal which are productive of the improved quality of reproduction attributed to it.

While in the foregoing there has been illustrated and described such combination and arrangement of elements as constitute the preferred embodiments of my invention, it is nevertheless desired to emphasize the fact that interpretation of the invention should only be conclusive when made in the light of the subjoined claims.

Having described my invention and its objects with such attention to detail as will thoroughly acquaint one skilled in the art with its construction and advantages, I claim:

1. A tubular graphophone needle for use with a reproducer, and having a body portion positioned to be inclined toward a record body and bent intermediate its ends to reduce the angular inclination of the lower end of the needle with respect to the record body, said body portion having its lower end gradually reduced in cross-section, an iridum point on the end of the reduced portion and having an angular inclination reverse to the angular inclination of the lower end of the body portion and laterally with respect to said body portion whereby to effectively contact with the groove of a record, and a member adapted to be inserted into the tubular portion of the needle to partially fill the same to intensify the reproduction of tones by the needle without effecting reproduction of stray noises incident to contact of the needle with a record.

2. A graphophone needle for use with a

reproducer, comprising a body portion positioned to be inclined toward a record and formed with a central cavity extending from end to end thereof whereby to soften the tones reproduced by the needle, said body portion being formed with a bend intermediate its length and gradually reduced from the bent portion to the lower end of the needle, a conical iridium point on the reduced end of the body portion and having an angular inclination reverse to the angular inclination of the lower end of the body portion and laterally with respect to said body portion whereby to provide a more effective contact with the groove, and a freely removable plunger of less length than the body portion and adapted to be inserted in the cavity above the bend in the body to partially fill the same to intensify the reproduction of tones by the needle without effecting reproduction of stray noises incident to contact of the needle with a record.

3. A graphophone needle comprising a body portion formed with a central cavity, said body portion being formed with a bend intermediate its length, a tapered point carried by the body portion and arranged to extend at an angle reverse to the angular inclination of the lower end of the body portion, and a freely removable plunger carried in the cavity of the body and extending to the bend therein for the purpose defined.

In testimony whereof, I affix my signature hereunto.

EPNST R. HAASE.
